(57) **CLAIM**

The ornamental design for a mount for track lighting fixture, as shown and described.

DESCRIPTION

FIG. 1 is a front elevational view of a mount for track lighting fixture showing my new design;

FIG. 2 is a back elevational view thereof;

FIG. 3 is a top plan view thereof;

FIG. 4 is a bottom plan view thereof;

FIG. 5 is a right side elevational view thereof; and,

FIG. 6 is a left side elevational view thereof.

The broken line depictions in the figures of a fixture and track connector are for illustrative purposes only and form no part of the claimed design.
